CLAIM

The ornamental design for a bagel cutter guide, as shown and described.

DESCRIPTION

FIG. 1 is a perspective view of a bagel cutter guide showing my new design;

FIG. 2 is a side elevation view thereof;

FIG. 3 is an end elevation view thereof;

FIG. 4 is a top plan view thereof; and,

FIG. 5 is a bottom plan view thereof.

The broken line showing the environmental structure of a bagel and knife blade in FIG. 1 is for illustrative purposes only and forms no part of the claimed design.
